(57) **CLAIM**

The ornamental design for a mower, as shown and described.

DESCRIPTION

FIG. 1 is a front-right perspective view of the a mower in accordance with the present invention;

FIG. 2 is a front left perspective view of the mower;

FIG. 3 is a plan view of the mower;

FIG. 4 is a front view of the mower;

FIG. 5 is a right side view of the mower;

FIG. 6 is a left side view of the mower; and,

FIG. 7 is a rear view of the mower.
